UNITED STATES PATENT OFFICE.

WALTER L. COURSEN, OF NEW ROCHELLE, NEW YORK, ASSIGNOR TO TUBIZE ARTIFICIAL SILK COMPANY OF AMERICA, A CORPORATION OF DELAWARE.

MULTICYLINDER PUMP.

Application filed February 11, 1927, Serial No. 167,436. Renewed June 16, 1928.

My invention relates to multicylinder pumps and has for its object to provide a pump especially well adapted for handling the viscous fluids used in the manufacture of 5 artificial silk filaments, such fluids for instance, as viscose or nitrocellulose collodion, in which mode of use the pumps may be said to act rather as regulators, providing for a constant rate of flow of the fluid through the spinnerettes than to perform the ordinary function 10 of pumps. While my improved pump is especially adapted for the purposes above noted, it is also usable for the ordinary purposes of pumps in general.

15 The special object of my invention is to provide a pump of such character that the moving parts will be thoroughly lubricated by the fluid passing through the pump and also of such a construction that the danger 20 of escape of fluid by leakage is minimized and the pressures within the pump balanced as nearly as possible.

25 The nature of my improvements will be best understood as described in connection with the drawings which illustrate my invention as applied in what I believe to be its best and most efficient form and in which

30 Figure 1 is a plan view of my pump shown partly in section on the line 1—1 of Fig. 4.

35 Figure 2 is a central sectional elevation of the pump shown in Fig. 1.

Figure 3 a cross section on the line 3—3 of Fig. 2 and

40 Fig. 4 a cross section on the line 4—4 of Fig. 2.

A is a fixed body in which, as shown, I form a bearing A¹ for the end of the actuating shaft and a series of cylinders A² extending through the body A from end to end. A³ and 45 A⁴ are passages formed in the body A and communicating respectively with the opposite ends thereof. A⁵ is an inlet passage formed in the body A, communicating, as shown, with the bearing A¹ and with a passage a¹ connecting with one end of the body A, as shown. A passage A⁶ leading from the other end of the body A communicates with the outlet port A⁷. B, B, etc., are cylindrical bushings fitting in the cylinders A² and having bores B¹ and B² of different diameters 50 communicating respectively with the end chambers of the pump. The bores B¹ constitute the pump cylinders proper and are provided with ports B³ and B⁴ diametrically opposite to each other and communicating re-

spectively with the passages A³ and A⁴. C, C¹ are differential pistons working in the cylinders B¹, B² and having extensions C² from the working face of the larger piston section, which, as the pistons revolve, alternately open and close the ports B³ and B⁴. The ends of differential pistons extend into the end chambers of the pump and are formed with hemispherical terminal ends C, C¹, for a purpose which will be explained, and to one end of the pistons are secured the gear wheels D, D.

60 End chambers, indicated at E¹ and F¹ are formed on each side of the fixed body A by means of caps E and F, the cap E being formed with an externally threaded stuffing box E² into which extends a gland E³, held in place and adjusted by means of the nut E⁴. The cap F is shown as formed with a threaded perforation F² through which extends a screw J supporting a hemispherical pivot, indicated at J¹.

70 G is a rotating shaft extending through the stuffing box into the chamber E¹ and having, as shown, a reduced end G¹ supported in the bearing A¹. I is a cam secured on the shaft G by key g and located in the chamber E¹, and H a gear wheel secured on the shaft and engaged with the gears D secured to the piston ends. K is a wobble plate centrally pivoted on the pivot J¹ and located in the chamber F¹. L, L, etc., are slippers or shoes resting in contact with the cam H and the wobble plate K and having spherical depressions in which fit the spherical ends c, c¹ of the piston ends. e and e¹ are grooves for fluid in chamber E¹ and e² a screw plug closing a port opening into groove e¹.

75 It will be seen that when the shaft G is rotated the rotating cam I and rotating gear wheel H will impart a reciprocating and rotating movement to the pistons, which are held in operative contact with the cam by the wobble plate K. During the suction stroke of the pistons the cylinder B¹ is, by the extension of the piston portion C, placed in communication with the port B³, passage A³ and chamber E¹, and during the compression stroke the cylinder is placed in communication with the port B⁴, passage A⁴ and chamber F¹. It will also be seen that the mechanism located in the chambers E¹ and F¹ is lubricated by the flowing mass of fluid passing through the pump, which also acts as a lubricant to the ends of the differential pistons. It will also be seen that the end thrust 100 105 110

on the pistons is only that due to the difference in the pressure existing in the chambers E^1 and F^1 .

Where the effective pressure exerted on the ends of the pistons extending into the chamber E¹ is greater than that on the ends of the pistons extending into the chamber F¹ it is obvious that the pistons will tend to remain in effective contact with the wabble plate K and that by adjusting the pivot J on which the wabble plate rests a regulation of the effective stroke of the pistons can be effected and this is desirable where the pumps are used, as they are primarily intended for use, in connection with an artificial silk spinning machine.

Having now described my invention, what I claim as new and desire to secure by Letters Patent is:

- 20 1. A multicylinder pump comprising a fixed body having formed in it a series of cylinders each having diametrically opposed inlet and outlet ports, passages connecting one set of said ports with a gear containing chamber into which the cylinders open at their ends and passages connecting the other set of which ports to a common exit conduit, in combination with a gear containing chamber at one end of the cylinder carrying body, a series of 25 pistons working in the cylinders and extending into the chamber, said pistons having extensions from their working ends which open and close the cylinder ports as the pistons rotate, and gear wheels secured to their ends 30 which extend into the end chambers, a rotating shaft entering the gear chamber having secured to it a cam for giving reciprocating motion to the pistons and a gear wheel engaged with the gears on the piston ends for 35 rotating the pistons, a conduit for fluid opening into the gear chamber and means for holding the pistons in operative relation to the cam.

40 2. A multicylinder pump comprising a fixed body having formed in it a series of cylinders each having diametrically opposed inlet and outlet ports communicating respectively with end chambers at each end of the cylinder containing body in combination with said chambers connected with inlet and 45 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends and a pivoted wabble plate located in the opposite end chamber and contacting with the piston ends extending into said chamber to hold them in contact with the cam.

50 3. A multicylinder pump comprising a fixed body having formed in it a series of cylinders each having diametrically opposed inlet and outlet ports communicating respectively with end chambers at each end of the cylinder containing body, in combination with said chambers connected with inlet and 55 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

55 4. A multicylinder pump comprising a fixed body having formed in it a series of cylinders each having diametrically opposed inlet and outlet ports communicating respectively with end chambers at each end of the cylinder containing body, in combination with said chambers connected with inlet and 60 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

65 5. A multicylinder pump comprising a fixed body having formed in it a series of cylinders each having diametrically opposed inlet and outlet ports communicating respectively with end chambers at each end of the cylinder containing body in combination with said chambers connected with inlet and 70 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

75 6. A multicylinder pump comprising a fixed body having formed in it a series of cylinders each having diametrically opposed inlet and outlet ports communicating respectively with end chambers at each end of the cylinder containing body in combination with said chambers connected with inlet and 80 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

85 7. A multicylinder pump comprising a fixed body having formed in it a series of cylinders each having diametrically opposed inlet and outlet ports communicating respectively with end chambers at each end of the cylinder containing body in combination with said chambers connected with inlet and 90 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

95 8. A multicylinder pump comprising a fixed body having formed in it a series of cylinders each having diametrically opposed inlet and outlet ports communicating respectively with end chambers at each end of the cylinder containing body in combination with said chambers connected with inlet and 100 outlet ports, rotating and reciprocating pistons the ends of which extend into the end chambers and which are formed to open and close the cylinder ports as they revolve, gear wheels secured to the piston ends which extend into one of the end chambers, a rotating shaft entering said end chamber having secured to it a cam for reciprocating the pistons and a gear wheel which engages and rotates the gears secured to the piston ends, an adjustable pivot and a pivoted wabble plate located in the opposite end chamber and contacting with the piston ends extending into said chamber to hold them in contact with the cam.

WALTER L. COURSEN.
